UNITED STATES PATENT OFFICE.

JOHN CORT, OF SEATTLE, WASHINGTON.

DESIGN FOR A NUT-LOCK WASHER.

SPECIFICATION forming part of Design No. 33,300, dated October 2, 1900.

Application filed June 2, 1900. Serial No. 18,906. Term of patent 14 years.

To all whom it may concern:

Be it known that I, JOHN CORT, a citizen of the United States, residing at Seattle, in the county of King and State of Washington, have 5 invented and produced a new and original Design for Nut-Lock Washers, of which the following is a specification, reference being had therein to the accompanying drawings.

Figure 1 is a plan view of a nut-lock washer, showing my new design. Fig. 2 is a side elevation, and Fig. 3 an end elevation, of the same.

My design for nut-lock washers consists in the shape or configuration shown in the drawings—namely, a flat body A, with a central perforation e and with four corners—one cor-

ner d being extended straight—that is, not bent—the opposite corner b being bent in one direction and the two remaining corners a c being bent in the opposite direction.

Having described my invention, what I claim as new, and desire to secure by Letters Patent, is—

The design for a nut-lock washer, as herein shown and described.

In testimony whereof I affix my signature in presence of two witnesses.

JOHN CORT.

Witnesses:

ARTHUR P. KNIGHT,
JAMES MCWILLIAMS.
